UNITED STATES PATENT OFFICE

2,441,744

COMBINED SCRAPER, GRADER,
LEVELLER, ETC.

Kenneth Barker, Boise, Idaho

Application December 11, 1944, Serial No. 567,746

3 Claims. (Cl. 37—129)

1

This invention relates to farm machinery and has for its object to provide a combined land surface scraper, loader, grader, spreader, etc.

Another object of the invention is to provide in a scraper a plurality of means whereby the depth of the cut may be regulated.

Another object of the invention is to provide in a scraper means whereby the contents may be evenly spread upon a desired surface, or dumped in a heap.

A further object of the invention is to provide in a scraper mounted upon wheels means whereby the weight of the load may be carried on the ground by the scraper, or upon the wheels, depending upon the distance to be hauled.

Another object of the invention is to provide a scraper so constructed that it may cut its swath close to a fence line, ditch, bank or other obstacle.

A still further object of the invention is to provide a scraper of substantially cylindrical or drum form and means whereby it may be raised vertically in order to avoid obstacles in its path.

Another object of the invention is to provide a rotatable drum scraper and grader.

A primary object of the invention is to provide a simple, effective and comparatively inexpensive tractor drawn scraper, designed especially for farm use, as well as by others having need for a small scraper, grader and dirt carrying combination unit of a practical nature.

Other features and advantages will become more readily apparent from the following description and the accompanying illustrative drawings.

Figure 1 is a side elevational view of my scraper.

Figure 2 is a top plan view thereof.

Figure 3 is a longitudinal sectional elevation thereof.

Figure 4 is a front elevational view of the machine.

Figure 5 is a rear elevation of the device.

Figure 6 is a view similar to Figure 3, partly broken away and shown in a changed position, and

Figure 7 is a sectional view taken at line 7—7 of Figure 1.

Figure 8 is a perspective view of the mechanism partly shown in Figure 7.

Like reference characters indicate like parts throughout the following specification and the various views in the drawings and in which: 10 indicates my scraping and grading machine as an entirety and 11 indicates a supporting frame

2

or chassis, at the rear ends 12 and 13 of which are provided U-bolts 14 and 15 for the reduced ends 16 of an axle 17 upon which wheels 18 and 19 are mounted. The parallel angle iron members 20 and 21, of the frame 11, are braced by a bar 22, just forward of the wheels. Another brace bar 23 connects the forward ends 24 and 25 of said members 20 and 21.

Located intermediate of the bars 22 and 23, 10 and upon the members 20 and 21, are bearings 26 and 27, in which are mounted stub shafts 28 and 29, attached to the center of side walls 30 and 31, of a substantially cylindrical or drum shaped combined scraper and load carrier 32 which is rotatable upon said stub shafts. The cylindrical wall 33 of the drum 32 is provided with an opening or mouth 34. Below said opening said wall is flattened as indicated at 35 and the flattened portion carries on its outer side a longitudinal scraper blade 36, the cutting edge 37 of which extends somewhat beyond the lower lip or edge 38 of said flat portion 35. A dog 39 is mounted upon the sidewall 30 of the drum and projects radially beyond the cylindrical wall 33. 15 It is adapted to rest upon a catch mechanism, generally designated by 40. Said catch mechanism 40 consists of two arms (Figs. 7 and 8) mounted on a shaft 45'. Between said arms a roller 44a is inserted carried by a bolt 43. On 20 this roller 44a the dog 39 rests when the drum is in the position shown in Figs. 1 and 3. The catch mechanism is normally held toward the drum 32 by means of a spring 41, connected at one end to an eye 42 on the bearing 26. A stop 25 46a on the member 20 fixes the position of the arm 44 and of the mechanism. The shaft 45' is supported by bearings on the frame ends 24 and 25. A similar dog 46, catch mechanism 47 and spring 48, is provided at the opposite side of the 30 drum. These dogs 39 and 46 hold the drum or pan 32 in scraping and filling position as shown in Figure 1 of the drawings. Another pair of dogs 49 and 50 is attached to the sidewalls of the drum and is adapted to hold the drum in upright 35 position (with its mouth 34 raised as in Fig. 6) when engaged to the catch mechanisms 40 and 47, when it is desired to haul the load a considerable distance. A third pair of dogs 51 and 52, attached to the drum in the same manner as the dogs above referred to, is adapted to engage 40 said catch mechanism to hold the drum in a position in which it can spread the load over the ground.

Pivotedly mounted on the bolts 53 and 54 on the 55 members 55 and 56 projecting up from an anchor

member 57 on the frame member 58 is a catch bar 59 formed of a pair of parallel bars 60 and 61, connected at their free terminal by a catch 62 adapted to engage one of the angle iron catch members 63 and 64 welded to the wall 33 in such spaced relation as to hold the drum 32, from reverse movement either when scraping, taking on a load or delivering the load. Fixedly mounted on the shaft 45', is a trip lever 65, which projects upwardly and passes between the members 60 and 61 of the catch bar 59; it carries the roller 66, mounted beneath said members 60 and 61, whereby, when the rope 67, secured in a bore 68 in the upper end of lever 65, is pulled the bar 59 will be raised and release catch 62, from the member 63 or 64, thus permitting the drum to rotate in reverse. Such reverse action results from engagement of the drum with the ground upon back up movement of a tractor to which the scraper is hitched.

Mounted under the forward end of the frame member 58, is a cylinder 70, in which is rotatably supported shank 71, of a hitch 72. Secured to the rear end of the member 71, is a collar 73, which bears against the rear edge of the cylinder 70, whereby the hitch is secured in place.

Adjustably attached to the member 57 by means of a U-bolt 75 fixed by nuts 92, is a depending leg 76, to the lower end of which is fixed a slide shoe 77, having its forward end 78, turned up to ride over obstacles. The primary purpose of this leg is to adjust the depth of the cut of the scraper blade. The depth of cut may also be adjusted through the raising or lowering of the hitch 72, on the draw bar of a tractor by which the scraper is drawn. The scraper drum 32 is provided with shoes 79, 80 and 81 for reinforcing the outer walls of the drum in order to avoid wearing of the wall when the drum has its mouth raised and is drawn upon the ground for a short haul.

It is to be noted that the retaining U-bolts 14 and 15, for the wheel axle 17 are attached to vertically disposed angle irons 82 and 83, secured to the frame ends 12 and 13, by welding or otherwise, the flange 84 and 85, of said irons being braced by members 86 and 87. The flanges 88 and 89 of said members 82 and 83 are each provided with a series of bores 90 and 91, within any pair of which said U-bolts 14 and 15, may be secured in order to adjust the wheels to conform with the height of the draw bar of a tractor to which the machine is to be attached, this being in order that the hitch 72, may be raised high enough to raise the drum 32, from the ground when necessary to carry the load in the drum a considerable distance or when it is necessary to raise the drum over an obstacle. The hitch 72, may be raised by raising the draw bar of the tractor. In most types of tractors such as at present in use the draw bar is provided with means for raising it, which in old constructions include chains or ropes and with more recent constructions include a hydraulic or screw operated lifting means driven by a motor. This customary draw bar lifting mechanism of the tractor is used, in the present case, to lift the frame to the desired position.

In operation the hitch 72 is attached to a tractor draw bar (not shown) which permits vertical adjustment of the connection of said hitch. The hitch is swiveled in order to accommodate uneven movement of either the tractor or the scraper. In order to scrape the surface of the ground, the drum 32 is rotated to bring its flattened surface 35 and the scraper blade 36, upon the ground, at which time the dog 39 is in engagement with the

roller 44a, which will prevent forward rotation of the drum and the catch 62 is in engagement with the catch member 63 on the drum, whereby it cannot rotate reversely, whereupon when the tractor moves forward the blade 36 cuts into the surface of the ground as indicated in Figures 1 and 3 of the drawings. As the tractor moves forward the upper surface ground is gradually forced into the drum until the same is filled or partially filled, whereupon by pulling on rope 67, the lever 65 is drawn forward and the roller 66 raises the catch bar 59, releasing the catch 62, permitting rearward rotation of the drum, whereby its mouth 34 will be brought to a raised position and the dog 49, pressing the catch mechanism 40 forwardly against the tension of spring 41 permits the dog to rise above said catch mechanism 40; the drum is stopped from forward rotation and may be dragged forward on the ground for short hauls. 10 In case of long hauls the tractor draw bar is lifted by the usual mechanism provided on the tractor for this purpose and the forward end of the frame is thus raised. This operation lifts the drum from the surface of the ground and throws the 15 weight of the load upon the wheels 18 and 19. In order to dump the load the rope 67 is drawn forward, rotating the shaft 45', releasing the member 40 from the member 49, permitting said member 49 through rotation of the drum to dig 20 into the ground and rotate the drum forwardly a sufficient distance to dump the load in a pile if desired to do so. However, if desired the tractor may move forward fast enough to permit the catch member 64 to be engaged by the catch 62. 25 In order that the load may be gradually spread upon the ground as the tractor moves forward the drum mouth 34, being close to the ground thus preventing pile dumping. When the drum is in this latter position, the inclined blade edge 37 30 will be in a substantially vertical position, whereby said blade as the tractor still moves forward will level the surface of the ground.

In order to regulate the depth of the cutter blade into the ground, the shoe leg 76 may be 45 raised or lowered through loosening of the nuts 92 of the U-bolt 75; after the adjustment is made said nuts are again tightened. Another means of adjusting the depth of the cut is through the 50 connection of the hitch with the tractor draw bar.

One great advantage of my scraper is obtained by making the drum wider than span between the wheels, so that the scraper may operate close to fence lines, banks, etc. A further advantage 55 of this arrangement is that the wheels move upon the scraped surface, therefore providing an even and level cut of the scraper. Another advantage of my design is that the scraper may be backed by the tractor over ditches, holes or other 60 places where it is not desired to move the tractor and the load dumped. It is of course obvious that the scraper blade can be removed for sharpening or renewing in case it becomes worn.

It is thought that persons skilled in the art to 65 which the invention relates will be able to obtain a clear understanding of the invention after considering the description in connection with the drawings. Therefore, a more lengthy description is regarded as unnecessary.

Minor changes in shape, size and rearrangement of details and parts such as come within the purview of the invention claimed may be resorted to, in actual practice, if desired.

I claim:

1. A combined scraper, load carrier and level-

ling machine, adapted for attachment to the liftable draw bar of a conventional tractor, comprising a liftable frame, a pair of wheels at its rear end, an axle for said wheels simultaneously serving as an axle for rocking said frame, means on the forward end of the frame to attach it to the draw bar of the tractor, a drum with an open mouth carried by and mounted for rotation on said frame in an intermediate position between the wheels and the forward end to be attached to the tractor, a scraper blade carried by said drum near said open mouth, stops for preventing the rotation of the drum in a forward direction on said drum, a rockable spring pressed catch mechanism for cooperating with said stops, a rocking shaft mounted on said frame, hand operated means for rocking said shaft including an operating lever, stops for preventing the rotation of the drum in a backward direction, a catch mechanism cooperating with said stops, said catch mechanism being brought into and out of engagement by the aforesaid lever mounted on the rocking shaft.

2. A combined scraper, load carrier and levelling machine, adapted for attachment to the liftable draw bar of a conventional tractor, comprising a liftable frame, a pair of wheels at its rear end, an axle for said wheels simultaneously serving as an axle for rocking said frame, means on the forward end of the frame to attach it to the draw bar of the tractor, a drum with an open mouth carried by and mounted for rotation on said frame in an intermediate position between the wheels and the forward end to be attached to the tractor, a scraper blade carried by said drum near said open mouth, three stops mounted on said drum for preventing the rotation of the same in a forward direction in three different positions of the drum, a rockable spring pressed catch mechanism provided with a catch member adapted to prevent rotation of said stops in one direction but permitting rotation past the catch mechanism in the other direction for changing the position of the drum, a rockable shaft for carrying said catch mechanism, a hand operated lever on said rockable shaft, means to operate said lever, stops on said drum for preventing the rotation of the drum in a backward direction, a catch for holding said stops so as to prevent rotation of the drum, a rockable lever carrying said catch mounted on the frame, said lever crossing the aforesaid lever on the rockable shaft and means including lifting stops for coupling said levers, so as to move the last named catch mechanism when the rotatable shaft is rocked.

3. A combined scraper, load carrier and levelling machine, adapted for attachment to the liftable draw bar of a conventional tractor, comprising a liftable frame, a pair of wheels at its rear end, an axle for said wheels simultaneously serving as an axle for rocking said frame, means on the forward end of the frame to attach it to the draw bar of the tractor, a drum with an open mouth carried by and mounted for rotation on said frame in an intermediate position between the wheels and the forward end to be attached to the tractor, a scraper blade carried by said drum near said open mouth, three stops mounted on said drum, for holding the same in three different positions against rotation in one direction, one of said positions corresponding to a substantially horizontal scraping position of the scraper blade, another position corresponding to a dumping position of the drum, and a third position corresponding to a load spreading position of the drum and to a levelling vertical position of the scraper blade, a rockable shaft on the frame, a catch mechanism mounted on said rockable shaft, spring operated means for holding said catch mechanism in operative stopping position relatively to the stops on the drum, adapted to permit passage of the stops in one direction, further stops on said drum for holding the same against rotation in a backward direction, a further catch mechanism cooperating with said stops, including a rockable lever fulcrumed at the forward end of the frame, an operating lever on the rockable shaft, means for rocking the same operated by hand, means on said last mentioned lever for lifting the first mentioned lever when operated to rock the shaft, an adjustable foot member on the forward end of the frame, for adjusting the scraping position, and means for adjusting said frame relatively to the wheels in a vertical direction.

KENNETH BARKER.
